UNITED STATES PATENT OFFICE

162,938

SUGAR BOWL OR SIMILAR ARTICLE

Rudolph Dopera, Los Angeles, Calif.

Application May 23, 1950, Serial No. 10,121

Term of patent 14 years

(Cl. D44—10)

To all whom it may concern:

Be it known that I, Rudolph Dopera, a citizen of the United States, residing at Los Angeles, in the county of Los Angeles and State of California, have invented a new, original, and ornamental Design for Sugar Bowl or Similar Article, of which the following is a specification, reference being had to the accompanying drawing, forming part thereof.

Fig. 1 is a top plan view of a sugar bowl showing my new design; and

Fig. 2 is a side elevational view thereof.

I claim:

The ornamental design for a sugar bowl or similar article, as shown.

RUDOLPH DOPERA.
